United States Patent Office

Des. 203,332

Patented Dec. 28, 1965

203,332

TOILET TISSUE DISPENSER

Council A. Tucker, Glendale, Calif., assignor to Towlsaver, Inc., Los Angeles, Calif., a corporation of California

Filed Sept. 28, 1964, Ser. No. 82,142

Term of patent 14 years

(Cl. D4—3)

FIG. 1.

FIG. 2.

FIG. 3.

FIG. 4.

FIG. 5.

The dominant features of my design reside in the portions shown in full lines and the tissue rolls are included in FIGS. 1, 2, and 5 for illustrative purposes only.

FIG. 1 is an isometric view of the toilet tissue dispenser showing my new design;

FIG. 2 is an end elevational view;

FIG. 3 is a top plan view;

FIG. 4 is a bottom plan view; and

FIG. 5 is a front elevational view.

I claim:

The ornamental design for a toilet tissue dispenser, as shown and described.
